UNITED STATES PATENT OFFICE.

GEORGE L. COMLOSSY, OF TOLEDO, OHIO.

DRAIN SEAL FOR REFRIGERATOR CARS.

Application filed February 2, 1925. Serial No. 6,344.

To all whom it may concern:

Be it known that I, GEORGE L. COMLOSSY, a citizen of the United States, and a resident of Toledo, in the county of Lucas and 5 State of Ohio, have invented a new and useful Drain Seal for Refrigerator Cars, which invention is fully set forth in the following specification.

This invention relates to liquid seals and 10 is more especially concerned with hydraulic seals for the drain pipes of refrigerator cars.

Practically for commercial purposes the transportation of perishable commodities such as fruit and vegetables presents certain 15 nice problems which have been the subject of increasing consideration because of the enormous loss which yearly occurs. Among the factors contributing to such commodity loss is the fact that the drain through which 20 flows the water from the melting ice is inefficiently sealed, and, as a result, in summer, warm atmospheric air enters the car causing melting of the ice and resulting deleteriously to the commodity, and, in winter 25 the cold air entering the car is also most injurious as will readily be understood. It has further been noted that in windy weather the hydraulic seal usually maintained to keep out atmospheric air and 30 retain the contained air is destroyed owing to the fact that the wind blowing up the drain pipe blows the liquid from the seal. It will be understood that the existing objections above noted are extremely detrimental 35 to efficient transportation of perishable commodities and the tremendous annual loss which is directly or indirectly due to these objections is staggering.

Objects of this invention are to provide a 40 liquid seal for drain ducts which prevents the ingress of atmospheric air irrespective of existing weather conditions; to provide a liquid seal for drain ducts of refrigerator cars which prevents the egress of the air 45 from within the car and the ingress of atmospheric air irrespective of surrounding weather conditions; and to provide a new and improved device which is readily attachable to and detachable from the ends of 50 pipes for effectively maintaining a liquid seal.

In one aspect this invention comprises a cup-like structure which may be of paper, cloth or other suitable material coated with 55 a suitable substance such as paraffin or other-

wise treated to render the cup resistant to liquids and alkalescent acids, the size and shape of the cup depending on the service conditions and the dimensions of the duct to which it may be detachably connected as 60 by an elastic band, bendable wire, etc. Suitably formed in the cup are one or more apertures through which liquid flowing through the duct may pass, the liquid flowing between the cup and the outer wall of the 65 duct so that in this manner a small amount of the liquid may be drained but sufficient will be retained to effect an adequate seal. It is to be understood that the size and strength of the cup as well as the strength 70 of the attaching or securing means may be varied in accordance with the prevailing service conditions, for example the cup and securing means may be of such size and strength to retain the duct full of liquid 75 or only sufficient liquid to provide a minimum seal. Such sealing device is most effective and useful in connection with drain pipes of refrigerating cars from which water resulting from the ice melting is drained 80 from the car and where an hydraulic or other seal is essential to prevent ingress of atmospheric air to the inside of the car and egress of the contained air to the atmosphere. 85

The invention is shown by way of illustration in the accompanying drawings, in which,—

Figure 1 is a fragmentary sectional view of a refrigerator car equipped with an hydraulic sealing device; 90

Fig. 2 is an enlarged sectional view showing in detail the liquid sealing device and operative arrangement of parts; and

Fig. 3 is a perspective of a modified form 95 of sealing device.

The illustrated embodiment of the invention comprises a refrigerator car 1 of any usual or well known construction having a compartment 2 for receiving perishable commodities such as fruit and vegetables, and a compartment or bunker 3 for receiving ice 4, the relatively warm air from compartment 2 entering compartment 3 through a screen 5 and returning to compartment 2 with the temperature considerably lowered through a screen 6. As the above construction forms no part of the present invention, further description thereof is deemed unnecessary. 110

The water resulting from the melting of the ice 4 is directed from the compartment 3 to a chamber or catch 7 by an inclined plate 8 and from the chamber 7 the water 5 flows by gravity into a drain pipe or duct 9. As has heretofore been pointed out, it is quite essential that the air within the refrigerator car be prevented from passing to atmosphere while at the same time atmospheric air must be prevented from entering 10 the refrigerator car and to accomplish this it has been found desirable and expedient to provide a water seal utilizing the water from the melting ice effectively to prevent the interchange of air at the different temperatures.

In accordance with the present invention a cup-like structure 10 is fitted over the end of the pipe 9 so that the end of the pipe 20 may be in close juxtaposition to the bottom of the structure. For securely holding the cup 10 in position on the pipe, annular grooves 11 may be formed in the outer surface of the pipe and an elastic band 12 of 25 rubber or other suitable material may be placed around the cup 10, pressing the material of the cup closely against one of the grooves 11. As shown, a plurality of 30 grooves 11 may be formed in the pipe 9 at vertically spaced intervals to accommodate 35 cups of different sizes, according to the seal desired or the weight of the débris issuing from the car or for other purposes. Formed in the cup 10 between the connection thereof 40 with the pipe 9 and the outer end of the pipe are one or more apertures 13, the number of 45 which may be varied according to the liquid flow from within the car.

In use the water flowing from the car 40 through the drain pipe 9 passes through the space between the cup 10 and the outer wall of the pipe and to the outside through the apertures 13 in the cup. It will thus be observed that so long as the cup remains 45 intact and in position on the drain pipe 9 an adequate liquid seal is formed which effectively prevents egress of air from within the car and ingress of atmospheric air to the inside of the car. When, however, the water 50 pressure becomes excessive or the weight of débris entering the cup overcomes the strength of the elastic band 12 the cup is automatically forced from engagement with the drain pipe and in this manner preventing 55 the water from backing up into the compartment 2 where it would otherwise injure or deteriorate the commodity and rot the car structure.

It is further to be observed that the cup 60 10 loosely enclosing the end of the drain pipe constitutes a collapsible structure which when subjected to external pressures greater than the pressures within the pipe 9, collapses against the outer wall thereof in order 65 to resist effectively any force tending to de-

stroy the seal. This is particularly advantageous when strong winds are blowing which otherwise would blow the liquid back up the pipe and into the interior of the car, resulting injuriously to the commodity and 70 car structure as above pointed out.

If it is desired to prevent freezing of the water forming the seal when the surrounding temperatures are relatively low, rock salt or other suitable material may be placed 75 in the bottom of the cup. However, under some circumstances, it may be desirable to permit the water in the pipe 9 and cup 10 to freeze and prevent the colder atmospheric air from entering the car and frosting, 80 freezing or otherwise injuring the commodity. If there is no ice in the bunker 3 there will, of course, be no water flowing down the pipe 9 to form a seal, so in this event the cup 10 may first be filled with 85 water or snow and then applied to the pipe, and in this manner an effective seal has been obtained with a minimum expenditure of time and trouble.

It is preferred that the cup 10 heretofore described be constructed of relatively heavy paper, paper substitute or similar flexible material which has been coated with paraffine or other suitable material which causes the structure to be reasonably resistant to 90 water and alkalescent acids, such construction being extremely simple so that the manufacturing cost is low, although efficiently obtaining the desired results.

As indicated in Fig. 3, the cup 10^a may be 95 constructed similarly to the cup 10, but in this instance the structure is made of cloth suitably treated to have proper resistant qualities above mentioned. Instead of employing an elastic band to hold the cup in position on the drain pipe 9, a wire 14 may be interlaced through the structure of the cup and the ends thereof project outwardly so that by the use of pliers or other suitable tool these projecting ends may be twisted 110 or bent thus securely to tighten the wire in one of the annular grooves 11.

It will be seen that I have provided a construction which satisfies the objects enumerated above and one which constitutes a valuable advance in the art. While I have shown the invention in certain physical embodiments, it is to be understood that modifications of the structure shown may be made by those skilled in this art without departing from my invention as expressed in the following claims.

What I claim is:

1. In a refrigerator car, the combination 125 with a drain duct leading from the interior thereof to the outside for permitting liquid to flow therethrough by gravity, of a flexible fabric structure enclosing the end of said duct, said device having apertures therein above the end of said duct to permit re-

stricted liquid flow therethrough, and means for removably connecting the upper portion of said device to said duct.

2. In a refrigerator car, the combination with a drain duct leading from the interior of the car for draining water melting from the ice contained therein to the outside by gravity, of a cup of flexible material enclosing the end of said duct and having apertures therein above the end of said duct for permitting liquid flow therethrough, and means for removably connecting the upper portion of said device to said duct.

3. In a refrigerator car, the combination with a drain duct for draining liquid from the interior of the car to the outside, of means enclosing the end portion of said duct for creating a liquid seal, said means consisting of a flexible fabric cup having a series of apertures arranged above the end portion of the duct, and means enclosing the cup above said apertures for removably connecting the cup to said duct whereby liquid may flow from the duct between the cup and outer wall of the duct and through said apertures.

4. In a refrigerator car, the combination with a drain duct for draining liquid from the interior of the car to the outside by gravity, of a flexible fabric device enclosing the end of said duct and having apertures therein above the end of said duct for permitting restricted liquid flow therethrough, and means for removably connecting the upper portion of said device to said duct, said duct having means cooperating with said connecting means for insuring against accidental detachment of said device.

5. In a refrigerator car, the combination with a drain duct for draining liquid from the interior of the car to the outside by gravity, of a flexible fabric cup enclosing the end of said duct and having apertures above the end of said duct, said duct having

an external groove, and means cooperating with said groove for removably connecting said cup to the outer wall of said duct.

6. A drain seal for refrigerator cars comprising in combination with a drain duct, means for creating a liquid seal at one end of said duct consisting of a flexible structure enclosing the end portion of said duct and having an aperture therein away from said end portion to permit limited egress of liquid from the duct and means for detachably securing said structure to said duct, said structure being of such character that when the pressure on the outside of said structure overcomes the liquid pressure the structure automatically collapses against the outer wall of the duct thereby preventing destruction of the seal by wind, etc.

7. A drain seal for refrigerator cars comprising in combination with a drain duct, a flexible structure loosely enclosing the end portion of the duct and having an aperture therein adjacent the free end thereof, and means for detachably connecting the structure to said duct, said structure being of such character that when wind blows against the duct sufficient to overcome the liquid pressure therein, the structure automatically collapses to prevent destruction of the seal.

8. A drain seal for refrigerator cars comprising in combination with a drain duct, a collapsible structure enclosing the end portion of said duct and having an aperture therein positioned away from the end of the duct, and means for removably securing said structure to the duct in such a manner that when the liquid or extraneous matter entering said structure exceeds a predetermined pressure or weight the structure is automatically disengaged from the duct.

In testimony whereof, I have hereunto signed my name to this specification.

GEORGE L. COMLOSSY.
